FARE RECEIVER

Gladstone E. Collins, Atlanta, Ga.

Application April 22, 1943, Serial No. 484,054

1 Claim. (Cl. 232—44)

This invention aims to provide an attachment for a fare box, which will facilitate the insertion of coins into the box, novel means being provided for holding the attachment in place, and novel means being supplied for adapting the attachment to fare boxes already in use.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows, in side elevation, a device constructed in accordance with the invention, mounted on a fare box;

Fig. 2 is a vertical section on the line 2—2 of Fig. 1;

Fig. 3 is a vertical section on the line 3—3 of Fig. 2;

Fig. 4 is a horizontal section on the line 4—4 of Fig. 1;

Fig. 5 is a perspective view delineating the device forming the subject matter of this application.

As to the fare-receiver shown in this application, the numeral 1 marks a fare box, on which is seated, detachably, a fare box head 2 having a recess 3 in its lower end, the head being of block-like construction. In its upper portion, the head 2 is provided with an opening 4 which tapers toward its ends, and inwardly and downwardly, in a well known way. At its lower end, the opening 4 communicates with a slot 5. In the slot 5 is disposed a two-part, downwardly extended coin chute 6, the constituent members of which are located side by side, as shown in Fig. 4. A transverse securing element 7, such as a pin, holds the coin chute 6 in the head 2, the securing element being supplied at its outer end with an enlarged head 8, provided with an opening 9. The head 8 forms one end portion of the securing element 7 and projects laterally beyond the member 2. The upper end of a flexible anchorage element 10, such as a light chain, is fastened in the opening 9 of the pin head 8, the opening forming means for engagement with the flexible element. The lower end of the flexi-

ble element is attached to the fare box. The purpose of the flexible member or chain is to prevent the part 2 from dropping to the floor, if it becomes accidentally detached from its place on the fare box.

It is with such a device, or with a similar device that the structure forming the subject matter of this application is adapted to be used.

The article forming the subject matter of this application, both *per se* and in combination with the part 2 of the fare box 1, includes a block-like body 11, superposed on the part 2 and provided at its lower end with depending flanges 12 and 14 defining a channel 15 in the lower portion of the body. In its lower end, the body 11 has a slot 16 of reduced width, and adapted to receive a coin. In its upper portion, the body 11 is provided with a downwardly tapered mouth 17, leading to the slot 16 and ultimately discharging into the coin chute 6. The opposed walls 18—18 and 19—19 of the mouth 17 converge downwardly, the walls 18 convexing toward each other, and the walls 19 convexing toward each other. The mouth 17 of the body 11, which constitutes a receiver, is larger than the opening 4 in the top of the head 2 of the fare box 1, and, on this account, the passenger can the more readily insert a coin, which finds its ultimate disposition in the fare box.

The head 2 of the fare box fits closely between the side flanges 12 and 14 of the receiver. Securing elements 20, located wherever desired, pass through the flanges 12 and 14 of the receiver and enter the head 2, to hold the parts specified firmly together.

There is a notch 21 in the lower edge of the flange 12 of the receiver, this notch being adapted for the reception of the head or laterally projecting portion 8 of the pin 7. In order to facilitate the assembly of the anchorage member 10 with the head 28 of the pin 7, by means of the opening 9, the body 11 is provided with an elongated, laterally open recess 22, leading downwardly to the notch 21, the inner wall of the recess having a downward and inward slant, as shown at 23. In connection with the mounting of the upper end of the flexible element 10 in the hole 9 of the pin head 8, it should be noted that the pin has a driving fit and is not a detachably mounted element.

Since the mouth 17 is of greater area at its upper end than the opening 4 of the head 2 of the fare box, the passenger or conductor has less trouble in inserting a coin into the fare box, and it is a matter of common knowledge that the en-

trance of passengers into a streetcar or the like should not be delayed by monetary transactions.

The flanges 12 and 14 define an open-ended trough in the body 11, wherein the head 2 is received, and since the head 8 of the securing element 7 is received in the notch 21, the mouth 17 is disposed directly above the coin chute 6, and the holes in the flanges 12 and 14 are lined up with the holes in the head 2, to receive the securing devices 20.

What is claimed is:

In a fare receiver, a fare box head, a coin chute in the head, a transverse securing element in the head and engaging the coin chute, one end portion of the securing element projecting laterally

beyond the head, a body superposed on the head and having a mouth discharging into the coin chute, the body having depending flanges defining an open-ended trough in which the head is received, one flange being provided in its lower edge with a notch receiving the laterally projecting portion of the securing element, the body and one of the flanges having openings, and a securing device in the openings and uniting the body with the head, the engagement of the laterally projecting portion of the securing element in the notch serving to dispose the mouth directly above the chute, and serving to align the openings for the reception of the securing device.
